STAND-BY FUEL CONTROL FOR JET ENGINES

Jack Isreeli, New York, and William Frantz, Lynbrook, N. Y., and Duncan Ramsay, Wahroonga, New South Wales, Australia, assignors to Simmonds Aerocessories, Inc., Tarrytown, N. Y., a corporation of New York

Application August 4, 1948, Serial No. 42,464

14 Claims. (Cl. 158—36)

1
This invention relates to improvements in fuel control apparatus for jet engines, and more particularly to stand-by control arranged to take over the metering of fuel to the jet engine in the event of a failure of the main control for the engine.

Jet engines are provided with a main control for metering fuel in accordance with given parameter selections or schedules for which the control and engine is designed. It is highly desirable to have a stand-by or auxiliary control apparatus which will take over the metering of the fuel in case of failure of the main control or of the pump, or other equipment involved in supplying fuel thereto.

The primary object therefore of the present invention is to provide a stand-by control apparatus which is associated with the fuel delivery line from the main control in such a way that it automatically takes over the fuel metering job upon the failure of the main control system or components.

According to the features of the invention, the improved apparatus comprises a combination of a stand-by fuel control system with a main control system and a pipeline for supplying fuel from a fuel supply and for delivering it to the nozzle gallery of the jet engine. The improved combination also includes a separate fuel supply line for the stand-by control system having a fuel metering mechanism associated therewith and connected into the line from the main control, a fuel return line for returning fuel from the said fuel supply lines to the supply tank or tanks, valve means for controlling the flow of fuel from each fuel supply line to the return line, a check valve in each of the fuel supply lines beyond the control valve, means for normally maintaining the control valve between the stand-by fuel supply line and the return line in open position, means for normally maintaining the valve between the main fuel supply line and the return line in closed position, and means responsive to a predetermined drop in the pressure of the fuel in the main fuel supply line in advance of the check valve therein for closing the control valve between the stand-by fuel supply line and the fuel return line.

The apparatus of the present invention also preferably includes means for shifting at will the control and metering of fuel from the main control system to the stand-by control system and vice versa. The apparatus is also desirably arranged so that where there has been a shift automatically from normal operation to emergency

5 control operation, the reverse shift will also take place if the main control comes back into normal operation. The combined systems are arranged to cooperate in maintaining fuel supply to the nozzle gallery of the jet engine or engines, and the stand-by control system is arranged to automatically supply fuel under metering conditions upon failure of the main control, such failure constituting or resulting in a reduction 10 in pressure in the fuel supply line from the main control to a value below the fuel pressure corresponding to maximum critical altitude of the engine or any other predetermined value.

Another feature of the invention comprises a 15 novel mechanism for operating the valves for bypassing fuel from the fuel supply lines to the return line, such mechanism including solenoid operated auxiliary valves of small capacity arranged to utilize fuel pressure for operating the 20 main bypass valves.

The apparatus of the present invention includes other features and advantages which will be described in greater detail hereinafter in connection with an apparatus comprising one illustrative embodiment of the invention as shown in the 25 accompanying drawing comprising a broken diagrammatic sectional view.

Referring to the drawing, the fuel normally supplied to the jet engine or engines is drawn from a supply tank through a supply line 10 and forced by means of an engine driven pump 12 through a line 14 which passes into a main metering control system, for example, of known type, shown diagrammatically at 16. The pump 12 may be an integral portion of control 16. From this main control, the metered fuel under normal operating conditions is conducted through a line 18 having a check valve 20 into a main supply line 22 which delivers the metered fuel 30 to the nozzle gallery of the jet engine or engines.

The fuel for the stand-by control is not taken from the pump 12, which may fail or be put out of action, but is supplied from the fuel supply tank through a separate line 24 and forced by 35 means of a pump 26, driven by any suitable power means, not shown, through a line 28 and metering mechanism 30 associated therewith, into a line 32 provided with a check valve 34, into the metered fuel line 22 leading to the nozzle gallery of the jet engine or engines.

The apparatus includes a pipe-line or duct 36 for returning fuel from either the line 28 or the line 18 to the supply tank, this line being connected into the line 18 by a branch line 38 controlled by a valve 40. Bypassed fuel from the

line 28 is delivered to line 36 through a branch line 42 controlled by a valve 44.

The valves 40 and 44 are constructed alike and provided with similar operating equipment. For example, the valve 40 is urged to its seated position, as shown, by a light spring, but is held in that position by the pressure of fuel from the line 18 supplied through a duct 46 opening into the line 18 and controlled by a small valve 48 operated by a solenoid 50. The space in back of the valve 40 is vented into the return line 38, and this vent is provided with an orifice 52. The arrangement is such that the pressure of liquid flowing through the duct 46 in back of the valve 40 holds it against its seat while a small amount of liquid continuously flows through the orifice 52. The valve 40 is held on its seat because of the equalized pressure in front and in back of the valve, coupled with the fact that the area of the back of the valve is greater than the area of the front of the valve projecting through its seat and facing into the line 18. When the small valve 48 is closed by the solenoid 50, the pressure in back of the valve 40 falls off because of leakage through orifice 52, so that pressure in the line 18 moves the valve 40 to open position, to permit the bypassing of fuel through the lines 38 and 36. The valve 44 operates in the same way and its associated elements are given the same numbers as the valve 40, plus the letter "a".

When engine fuel is being supplied under control of the main system 16, that is, through the line 18, the valve 40 is closed and the valve 48 open, while the valve 44 is open and the small solenoid operated valve 48a is closed. The fuel flowing through the line 18 therefore opens the check valve 20 and fuel pressure closes the check valve 34.

A differential pressure switch mechanism is associated with the line 18 and responsive to a pressure drop therein for de-energizing the solenoid 50a, opening valve 48a and effecting the closing of the valve 44 so that fuel will be supplied through the lines 28 and 32 to the engine supply line 22. This mechanism includes a shuttle like actuator 54 urged to its upper position by a spring 56 and urged to its lower position against the spring by the pressure of fuel from the line 18 supplied through a duct 58, an adjustable pressure relief valve 60 and a duct 62. The actuator 54 is provided with an external cam-like surface 64 which engages and moves a pin 66 when the actuator is pushed down by the pressure of the fuel. The actuator 54 is also drilled as shown and provided with an orifice 68 through which fuel may flow into the lower portion of the valve cavity and through a duct 70 to a fuel return line such as 36. When the pin 66 is moved to the right by the shuttle like actuator 54, it moves a block 71 on a diaphragm seal to in turn move a pin 73 to close the contacts 72 of a switch 74. This switch is pivoted in its mounting on a pin 75, at its upper right-hand corner, and is adjustable with respect to the block 71 by a spring 75a and screw 75b as shown. The switch 74 may be pivoted on the pin 75 with or against the action of the spring 75a by operating the screw 75b so that the switch contacts 72 will be open when the actuator 54 is up and will be closed when the actuator 54 is pushed down to the desired extent by the fuel pressure.

The adjustable pressure relief valve 60 is mounted in a cavity and is responsive to the pressure in the line 18. This valve is adjusted

by a screw 76 and associated spring to control the pressure at which the stand-by system will be cut in and out. When the pressure in the line 18 is up to normal operating pressure the valve 60 will be in its upper position so that fuel will flow through lines 58 and 62 and force the shuttle like actuator 54 down, thereby closing the switch contacts 72. The cavity of the adjustable valve 60 and the cavity to the left of the diaphragm carrying the block 71 are vented to fuel return by lines 77 so that the valve 60 moves freely in response to the pressure in the fuel line 18, and pressure is not built up against the diaphragm by leakage around pin 66.

The contacts 72 of the switch 74 are connected by wires 78 and 80 to the terminals of a switch 82, the wire 78 also being connected into an associated source of electric current such as a battery 84, while the wire 80 is also connected by wires 86 to the solenoid 50a. The battery 84 and solenoids 50 and 50a are grounded. It will be seen that as long as the contacts of switch 74 are together, current flows from the battery 84 through the wire 78, the switch contacts 72, the wires 80 and 86 and the solenoid 50a, so that the latter is energized to keep the valve 48a closed and permit the opening of the valve 44. This is the position of the apparatus during normal operation of the system, it being understood of course that the main control 16 is set by levers 88 connected to the pilot's, or the operator's control lever 90.

If for any reason the pump 12 or the main control 16 should fail and the pressure of fuel in the line 18 fall off to the predetermined set value, the valve 60 would close off the flow of fuel through the line 62 and the shuttle like actuator 54 would assume its upper position under action of the spring 56 because of the leakage through the orifice 68. This will cause separation of the contacts 72 and the deenergizing of the solenoid 50a, which would permit the flow of fuel through the duct 46a to equalize the pressure on opposite sides of the valve 44, thereby permitting the spring to move it to closed position, so that fuel would then be supplied to the engine from the stand-by control system, including the line 32. As soon as pressure builds up in the lines 32 and 22, the check valve 20 will automatically be closed.

The stand-by control apparatus is arranged so that the pilot or operator may deliberately select it at any time by pressing a switch button 92 which operates a switch 94. As an example, if the pilot or operator desires to use the stand-by control in starting the engine, he pushes down on the button 92 to close the switch 94. It will be noted that at this time with no fuel pressure in line 18, the shuttle like actuator 54 is up. The switch 82 is open and the solenoid 50a is de-energized so that valve 44 will close as pressure builds up in the line 28. The closing of the switch 94 sends current from the battery 84 through a wire 96 to the solenoid 50 to close the valve 48, which results in the opening of the valve 40 when fuel pressure develops in the line 18 as the engine starts, the pump 12 being an engine-driven pump. After the stand-by control is once selected by operation of the switch handle 92, it will continue operation until the switch handle is raised. Once the switch handle is raised, the main control will come into operation in the manner explained above and override the stand-by control.

The main and stand-by controls are advantageously correlated so that the stand-by control

is designed to meter fuel in sufficient quantity to maintain engine operation and at some fuel pressure value below that selected for the main control. Therefore, as long as the main control operates normally, its pressure overrides the potential pressure of the stand-by control and actuates the shuttle valve 54 so that the solenoid 50a is energized and the valve 44 opened. From the foregoing it will be understood that if the main control should operate erratically, the pilot or operator may put it out of action at any time and elect to control the engine with the stand-by control by merely closing the switch 94 while maintaining switch 82 open.

When it is desired to cut off the supply of fuel to the engine, both solenoids 50 and 50a are energized by pressing the switch button 92 and a switch button 98 which respectively close switches 94 and 82. The valves 40 and 44 are then permitted to open, regardless of which control system is being used. The springs of the check valves 20 and 34 are rated with respect to the springs of the valves 40 and 44 so that they will close, while the valves 40 and 44 may be pushed open.

The metering system included in the stand-by control apparatus and connected between the fuel supply lines 28 and 32 includes combinations of elements arranged to utilize various orifice sizes and varying fuel pressures. It is to be understood that flow through a fixed orifice can be controlled by varying the pressure drop across it; or for constant pressure drop, flow may be controlled by varying the area.

The stand-by control in the present instance is arranged to supply fuel to the engine according to a given speed selection schedule and according to the total intake pressure received by the engine. The speed scheduling is obtained by the pilot's operation of a rotary speed jet device 100 opening into the line 28 and connected to a lever 102 having a linkage 104 connected with the linkage 88 and the pilot's control lever 90. The speed jet device 100 includes an open-top rotatable cylinder 105 connected to lever 102 and having a variable area orifice 106 which delivers fuel through a duct 107 of oblong cross-section opening through a cylinder surrounding the cylinder 105 and arranged to take the flow through whatever area of the orifice coincides with the inlet of the duct 107. When the pilot rotates the cylinder 105 of speed jet 100 he selects a particular area for the flow of fuel, this area representing the desired speed selection.

The fuel delivered through the duct or passageway 107 flows through ports 108 in a regulator valve body 110 and then into line 32 containing the check valve 34.

The regulator valve body 110 carries a closure member 112 urged away from its seat by a spring 114 and urged to its seat by the pressures acting across a diaphragm 116 attached to a valve shaft 118.

Metering pressure across the speed jet 100 is regulated by movement of the valve closure member 112 in conjunction with a barometric jet 120, a diaphragm assembly 122 and an adjustable jet 124. The stem of the barometric jet carries a barometric bellows 126 of known type and function mounted in a chamber 128 connected to the air intake of the engine by a duct 130, so that the pressure around the bellows 126 is the total engine intake pressure. The flow area at the barometric jet 120 may be adjusted by a threaded adjusting screw 132 attached to the bellows.

126. The barometric jet provides an altitude regulating valve for the flow of fuel from the chamber between the diaphragms 116 and 122, this fuel being passed through a duct 134 into the space in back of the diaphragm 122 and then through a control passageway 135 into a fuel return line 136 leading to the line 36. Any leakage around the needle of the barometric jet also flows into the line 136 from a duct 137. The diaphragm 122 carries a pin 138 for controlling passageway 135 and is biased to the right by a spring 139.

The barometric bellows 126 varies the area at the barometric jet 120 as a function of the total intake pressure. Any variations in the total intake pressure causes a corresponding change in position of the needle of the barometric jet and in the flow therethrough. This flow can be made any function of the total intake pressure desired by profiling the barometric jet appropriately.

In equilibrium the forces on either side of the flexible diaphragm 122 must be equal. Thus the pressure on the spring side of the diaphragm is less than on the opposite side since the spring load plus the pressure load on one side must equal the pressure load on the other side. If the spring load plus pressure load is too low, pin 138 is moved toward closing till pressure increases. The opposite action is true if the opposite loading is true. The resulting pressure differential acting across diaphragm 122 which is maintained essentially constant by proper detail design acts in conjunction with the area of jet 120 to flow a quantity of fuel through jet 120 which is a function of total intake pressure. The total fuel flowing through the barometric jet 120 must come through the adjustable jet 124 which takes fuel at the pressure in the line 28 through a line 140, the fuel passing the jet 124 being delivered through a line 142 into the chamber between the diaphragms 116 and 122. The only outlet to this chamber is through the barometric jet 120. Pressure drop across jet 124 may be adjusted by turning the threaded stem 144 when the apparatus is tested to give the desired flow through the stand-by control. As a result of the relationships, described above, between the barometric jet 120 and its associated diaphragm assembly, the flow through the adjustable jet 124 is a function of the total intake pressure of the engine.

The adjustable jet 124 and the speed jet 100 are supplied with fuel from the same intake line 28, therefore, the pressures in the inlet to these jets are equal. The pressure drop across the adjustable jet 124 creates a metering pressure across the speed jet 100 in the manner described below.

The diaphragm 116 may be referred to as a speed regulating diaphragm and it, in conjunction with the valve member 112, actuated thereby, maintain the outlet pressure at the adjustable jet 124 and the speed jet 100 equal to each other. An increase in pressure between diaphragms 116 and 122 tends to move the valve member 112 toward its seat until the outlet pressure at the speed jet is made substantially equal thereto. Therefore, the flow through the speed jet is determined by the area set by the pilot's lever which is a function of the selected speed, and by the metering pressure which is a function of the total intake pressure.

On one side of the diaphragm 116 the total force acting is equal to the pressure at the outlet of jet 124 times the diaphragm area. On the other side the total force equals the pressure

existing at line 32 times the area of line 32 plus the pressure at the line 107 times the remaining area at the diaphragm 116. The pressure at line 32 varies continually throughout an operating period and the resultant change in the pressure at line 107 can adversely affect accuracy of metering into line 22 except for the action of spring 114. As pressure at line 32 varies, valve 112 varies its position in order to create the appropriate pressure drop between line 107 and line 32. The varying position and load of and across valve 112 is matched by the position and loading of spring 114 so that the pressure at line 107 is maintained essentially constant with the changes in pressures at line 32, thereby improving the accuracy of metering.

The apparatus of the present invention, including a combination of a stand-by control with a main control for a jet engine, provides a system which is automatic and effective for metering fuel to the jet engine. The stand-by control of the improved system furthermore is arranged to effectively meter fuel to the engine advantageously at a rate slightly less than that supplied by the main control. The main control may govern the speed of the engine directly, while the stand-by control of the present apparatus associated therewith governs the speed of the engine by scheduling fuel delivery according to engine speed and total intake pressure.

From the foregoing description of the invention, it will be apparent that certain changes may be made in various elements of the apparatus without departing from the spirit and scope of the invention, as defined by the appended claims.

What is claimed as new is:

1. In an apparatus for controlling the supply of fuel to jet engines including a main control and a stand-by control, means including a pipeline for supplying fuel from a fuel supply and for delivering the fuel to the jet engine nozzle gallery, the fuel in said line being under control of the main control, a separate fuel supply line for supplying fuel from a fuel supply to the stand-by control and connected into the line from the main automatic control leading to the engine nozzle gallery, a fuel return line connected into each of said fuel supply lines, valve means for controlling the flow of fuel from each fuel supply line to the return line, a check valve in each of the fuel supply lines beyond said control valves, means for normally maintaining the control valve between the stand-by fuel supply line and the return line in open position, means for normally maintaining the valve between the stand-by fuel supply line and the return line in closed position, and means responsive to a predetermined drop in pressure in the main fuel supply line between the main control and the check valve in the line for closing the control valve between the stand-by fuel supply line and the fuel return line.

2. An apparatus for controlling the supply of fuel to jet engines as defined by claim 1 in which each control valve includes a piston-like valve member, and a solenoid means for controlling the movement of the piston-like member.

3. An apparatus as defined by claim 2 in which each valve member is mounted in a cylindrical chamber, a passageway for fuel from the fuel supply line to the back portion of the chamber in which the piston-like member moves, a passageway having an orifice therein leading from said chamber to the return line, and a small valve actuated by the solenoid means arranged to open

and close the passageway from the fuel supply line.

4. An apparatus for controlling the supply of fuel to jet engines as defined by claim 1 in which the control valve between the stand-by fuel supply line and the fuel return line includes a piston-like valve member mounted for reciprocation in a chamber, a passageway leading from the stand-by fuel supply line to the chamber in back of the piston-like member, a passageway having a leakage orifice leading from said chamber into the fuel return line, a small valve in the passageway leading from the stand-by fuel supply line, a solenoid for operating said small valve, and means associated with the responsive means for controlling the energizing and the de-energizing of the solenoid.

5. An apparatus for controlling the supply of fuel to jet engines as defined by claim 1 in which the means responsive to a predetermined drop in pressure comprises an electric switch, an actuator means for operating said switch, and means for conducting fuel from the main fuel supply line between the main control and the check valve therein to said actuator means.

6. An apparatus as defined by claim 5 in which said actuator means includes a reciprocable piston-like shuttle member, means for biasing said shuttle member, and a valve in the passageway leading to the shuttle member and responsive to the fuel pressure in the passageway.

7. An apparatus for controlling the supply of fuel to jet engines as defined by claim 1 in which each control valve includes a relatively small solenoid-operated valve for controlling the actuation of a valve member for in turn controlling the flow of fuel to the return line, and means for energizing and deenergizing the solenoids of the solenoid valves.

8. An apparatus for controlling the supply of fuel to jet engines as defined by claim 1 in which the stand-by control is mounted in the stand-by fuel supply line between the control valve and the check valve therein, the stand-by control including a speed jet through which fuel for the jet engine flows, and means for controlling the metering through said speed jet responsive to the total intake pressure of the engine.

9. An apparatus as defined by claim 8 in which the speed jet includes pilot-controlled means for varying the area of the jet through which the fuel flows, a valve in the fuel supply line immediately following the speed jet, and means responsive to changes in pressure of the fuel after leaving the jet for controlling the valve in the line directly after the jet.

10. An apparatus for metering fuel supplied to an engine, comprising a fuel supply line, a speed jet in said line, means for manually controlling the flow area of said jet, a diaphragm control valve in the line downstream from the jet, the diaphragm being responsive to the pressure of the fuel flowing from the jet, a second diaphragm spaced from the diaphragm of the diaphragm valve and forming a chamber therebetween, means for bypassing a restricted flow of fuel from the fuel supply line around the speed jet to said chamber, a passageway from said chamber to the space in back of the second diaphragm, and means responsive to the total intake pressure of the engine for controlling the flow through said passageway.

11. An apparatus as defined by claim 10 in which the valve downstream from the speed jet includes a movable member movable to open

position by a biasing spring and toward a closed position by the diaphragm associated therewith, said second diaphragm being biased toward said chamber by a biasing spring, and means movable by said second diaphragm for varying the flow of fuel in said passageway.

12. An apparatus for controlling the supply of fuel to jet engines as claimed in claim 1, characterized in that the stand-by control is arranged in the stand-by fuel supply line between the control valve and the check valve therein and comprises a speed jet in the stand-by fuel supply line, means for manually controlling the flow area of said jet, a diaphragm control valve in the stand-by line down-stream from the jet, the diaphragm being responsive to the pressure of the fuel flowing from the jet, a second diaphragm spaced from the diaphragm of the diaphragm valve and forming a chamber therebetween, means for by-passing a restricted flow of fuel from the stand-by fuel supply line around the speed jet to said chamber, a passageway from said chamber to the space in back of the second diaphragm, and means responsive to the total intake pressure of the engine for controlling the flow through said passageway.

13. In an apparatus for controlling the supply of fuel to jet engines including a main control and a stand-by control, means including a pipeline for supplying fuel from a fuel supply and for delivering the fuel to the jet engine nozzle gallery, the fuel in said line being under control of the main control, a separate fuel supply line for supplying fuel from a fuel supply to the stand-by control and connected into the line 35 from the main automatic control leading to the

engine nozzle gallery, fuel return line means connected into each of said fuel supply lines, valve means for controlling the flow of fuel from each fuel supply line to the return line means, check valve means for each of the fuel supply lines beyond said control valves, means for normally maintaining the control valve between the stand-by fuel supply line and the return line in open position, means for normally maintaining the valve between the main fuel supply line and the return line in closed position, and means responsive to a predetermined drop in pressure in the main fuel supply line between the main control and the check valve means in the line for closing the control valve between the stand-by fuel supply line and the fuel return line.

14. An apparatus for controlling the supply of fuel to jet engines as defined by claim 13 in which the means responsive to a predetermined drop in pressure comprises an electric switch, an actuator means for operating said switch, and means for conducting fuel from the main fuel supply line between the main control and the check valve means therein to said actuator means.
